FRAME

Paul H. Ostrander and Frederick Charles Herby,
Jamestown, N. Y.; said Ostrander assignor to
said Herby

Application November 28, 1932, Serial No. 644,610

5 Claims. (Cl. 88—97)

This invention relates to an improvement in frames and the supporting means therefore.

The present invention is directed to the provision of a mirror or other frame having means for securing a backing plate thereto and on which plate, lugs or other projections are located for the purpose of supporting said frame on a wall mounted bracket.

One of the objects of the invention lies in the provision of a frame having supporting means attached thereto for removable engagement with a wall bracket.

Another object of the invention lies in the provision of a frame having means by which to support it in two or more positions on a wall mounted bracket.

A further object of the invention lies in the provision of means attachable to any wall fixture for the purpose of removably mounting said fixture on a wall supported bracket.

A still further object of the invention lies in the provision of a wall mounted bracket having means for receiving and securing a lug joined to a frame or other wall type fixture.

Other and further objects of the invention will be more clearly understood from a consideration of the following specification in conjunction with the accompanying drawings and in which,

Figure 1 is an elevation of a mirror or other frame which is supported in a horizontal position by means constituting a part of the invention;

Figure 2 is an elevation of the frame supported in a vertical position by the same means;

Figure 3 is a rear elevation of the frame showing the supporting lugs;

Figure 4 is a fragmentary perspective view of the wall bracket by which the frame is supported;

Figure 5 is a fragmentary vertical sectional view taken substantially on the line 5—5 of Figure 1;

Figure 6 is a perspective view of a shelf supported in the same manner as the frame shown in Figure 5;

Figure 7 is a vertical sectional view taken substantially on the line 7—7 of Figure 6;

Figure 8 is an enlarged horizontal sectional view of the frame taken substantially on the line 8—8 of Figure 2;

Figure 9 is a horizontal sectional view of the frame taken substantially on the line 9—9 of Figure 1; and

Figure 10 is a perspective view of the spring retainer.

Referring to the drawings and particularly Figures 1 to 7 inclusive, there is shown a frame supporting unit generally indicated by the reference numeral 10 which comprises a channel shaped wall bracket 11 having upper and lower edge flanges 12 and 13 respectively, and a base wall 14. The bracket is mounted on a building wall by suitable screws 16. One or more V-shaped slots 17 are formed in the base wall 14. These slots are continued through the horizontal flange 12 for the purpose of facilitating mounting or dismounting of a lug 18 relative to said bracket. The bracket is preferably provided with two slots 17, one at each end thereof, to insure at least a two point contact with the frame. The lug 18 is riveted, screwed, or otherwise suitably joined to the backing plate 19 of the frame 21. The head of the lug is formed with converging walls which terminate in a collar 20. The purpose of the collar and the converging walls may be clearly understood from an examination of Figures 5 and 7 of the drawings, wherein it is shown that the collar constitutes a portion against which the wall 14 of the bracket abuts, the converging walls of the head 20 of lug acting, when the lug is moved downwardly in the slot 17, to so dispose said lug. It will be noted from an examination of Figure 3 that the backing plate 19 is provided with four lugs 18 which are arranged in the form of a square having sides substantially equal to the distance between centers of the two slots 17. The purpose of this arrangement is to provide a certain amount of adjustment in mounting the frame. In the horizontal position, the frame may be supported by either the upper or lower pair of lugs, depending upon the location desired. The frame may be supported in a vertical position as shown in Figure 2, by utilizing a different combination of lugs.

Figures 6 and 7 of the drawings illustrate another adaptation of the device in connection with supporting a shelf 23. The shelf is provided with a cutout 24, one edge of which is adapted to receive the bracket 11. Located within the cutout, are lugs 26 which are similar to lugs 18 except that they are provided with a wood screw portion 27. The ends of the shelf are provided with the usual braces or angle pieces 28, one vertical edge of each of which is adapted to rest against the building wall when the shelf is mounted.

No attempt will be made to illustrate further applications or adaptations of the invention.

since the present showings are sufficient to disclose the adaptability of the bracket and lugs.

Figures 8 through 13, illustrate the construction of a mirror and frame which is provided with the above described wall support. The frame 29 is angular in cross section, having flanges 31 and 32. Flange 31 engages the face of the mirror 33, and flange 32, extending at right angles to the flange 31, terminates in a hook portion 34. The backing plate 19 contacts with the rear face of the mirror 33 and is held in position within the frame 29 by means of one or more leaf spring retainers 35, the ends of which terminate in portions 36 which are bent slightly from the plane of the center portion. These portions are adapted to contact with the hook portion 34 of the frame in the manner shown in Figure 11. Thus the spring 35 frictionally retains the mirror and the backing plate in the proper position relative to the frame.

To assemble this structure, the mirror is first placed face downwardly against the flanges 31 of the frame. The backing plate 19 is then placed on top of the rear face of the mirror. Next the spring retainers are inserted and the bent portions 36 depressed and moved into engagement with the inner edge of the hook portion 34. The spring tension thus produced between portions 34 and flanges 31, secures the mirror and backing plate 19 against displacement and at the same time is sufficiently yielding to constitute means for absorbing shocks, which would tend to break the mirror, when the device is dropped or otherwise mishandled. In the present showing, there are three such springs applied to the mirror. It is apparent, however, that more or less may be utilized as desired.

To mount the mirror on the wall, the bracket 14 must first be secured thereto by means of the screws 16, so that the apex of the V-shaped slots 17 point downwardly as shown in Figure 4 of the drawings. The lugs 18 on the backing plate of the mirror are caused to register with the slots 17. The converging surfaces of the lug, when brought into contact with the converging walls of the slot, causes said lug to be urged toward the building wall. The combined weight of the mirror and frame is sufficient to produce pressure contact between the rear edges of the mirror and the surface of the wall and prevent inadvertent dislodgement therefrom.

Although applicants have shown and described only two modifications of their invention, it is

not intended that they be limited thereto, since other modifications or adaptations may be made without departing from the spirit and scope of the invention as defined in the hereunto annexed claims.

Having thus set forth my invention what I claim as new and for which I desire protection by Letters Patent is:

1. A frame for mounting on a wall including a backing plate, spring means securing said plate to said frame, projections on said plate, a bracket having a slotted wall, said projections being interengageable with the slotted wall of said bracket whereby to support said frame.

2. A frame for mounting against a building or other wall, a plate in said frame, a lug on said plate, a tapered portion on said lug, spring means releasably joining said plate to said frame, a bracket secured to said building wall, said bracket including a V-shaped slot, said lug being engageable with the walls of said slot, said tapered portion serving to move said frame laterally into abutment with said building wall during the engaging of said lug with said slot.

3. A frame for mounting against a building or other wall, a plate in said frame, a lug on said plate, said lug being located within the limits of said frame, spring means releasably joining said plate to said frame, a bracket supported on said building wall, said bracket including a V-shaped slot for receiving said lug, said bracket being receivable into said frame to permit abutment of said frame against said building wall.

4. A frame for mounting in abutment with a building or other wall, a plate on said frame, spring means releasably joining said plate to said frame, a wall mounted bracket, interengageable means on said plate and said bracket, and further means, said further means serving to displace said frame in a direction perpendicular to its direction of movement during the operation of engaging the plate and bracket elements.

5. A frame for mounting against a building or other wall, a plate in said frame, spring means releasably joining said plate to said frame, a bracket secured to said building wall, interengageable elements on said plate and said bracket, and means on one of said elements displacing said frame in a direction perpendicular to its direction of movement during the operation of engaging the plate and bracket elements.

PAUL H. OSTRANDER.
F. CHARLES HERBY.
